UNITED STATES PATENT OFFICE

113,336

DESIGN FOR A SMOKER'S ASH STAND

Jacob I. Russakov, Chicago, Ill.

Application August 1, 1938, Serial No. 79,013

Term of patent 7 years

To all whom it may concern:

Be it known that I, Jacob I. Russakov, a citizen of the United States, residing in Chicago, Cook County, Illinois, have invented a new, original, and ornamental Design for a Smoker's Ash Stand, of which the following is a specification, reference being had to the accompanying drawing, forming a part thereof.

The figure is a perspective view of a smoker's ash stand showing my new design.

Characteristic features of the design reside in the combination of the handles and stand pillar of the specific configuration shown, the handles comprising two straight bars positioned in paral-

lel relation to the stand pillar adjacent the top thereof, each handle being supported by two members projecting at right angles from the stand pillar and engaging the handles at intermediate points therein uniformly spaced apart from the ends of the handles; the said members having a metallic finish and the handles and stand pillar being of contrasting colors, the stand pillar being of a dark color and the handles being of a light color.

I claim:

The ornamental design for a smoker's ash stand, substantially as shown and described.

JACOB I. RUSSAKOV.
